INVENTOR.

UNITED STATES PATENT OFFICE.

FRANK C. BARNES, OF FREMONT, OHIO.

SYRINGE.

No. 880,496.

Specification of Letters Patent.

Patented March 3, 1908.

Application filed June 11, 1907. Serial No. 378,399.

To all whom it may concern:

Be it known that I, FRANK C. BARNES, a citizen of the United States, residing at Fremont, in the county of Sandusky and State of Ohio, have invented a new and useful Syringe, of which the following is a specification.

This invention relates to syringes and has for its principal object to provide a syringe 10 of very simple and economical construction having both influent and effluent tubes and in which provision is made for adjusting the position of the effluent tube or nozzle so that the discharge may be drained off at any 15 desired point.

A further object of the invention is to provide a device of this character in which the several parts may be readily detached, and further to provide for the employment of 20 interchangeable cap pieces of different size so that the length of the syringe may be altered as required.

With these and other objects in view, as will more fully hereinafter appear, the invention 25 consists in certain novel features of construction and arrangement of parts, herein-after fully described, illustrated in the accompanying drawings, and particularly pointed out in the appended claims, it being understood 30 that various changes in the form, proportions size and minor details of the structure may be made without departing from the spirit or sacrificing any of the advantages of the invention.

35 In the accompanying drawings:—Figure 1 is a sectional elevation of a syringe constructed in accordance with the invention. Fig. 2 is a sectional plan view of the same on the line 2—2 of Fig. 1. Fig. 3 is an end elevation of the device. Fig. 4 is a transverse sectional view on the line 4—4 of Fig. 1. Fig. 5 is a detail view of a modification.

Similar numerals of reference are employed 45 to indicate corresponding parts throughout the several figures of the drawings.

The syringe forming the subject of the present invention is made of hard rubber, aluminium or other suitable material, and includes a head member 10 and a base 11, 50 these being united by a plurality of integral bars 15 that are spaced from each other in order to permit the ready outflow of the discharge.

The head 10 has a reduced threaded for- 55 ward end on which may be screwed a cap piece 16 that is provided with perforations for the

lateral discharge of the spray, the device being so constructed that cap pieces of any size may be employed for the purpose of altering the length of the syringe, as desired. The 60 head 10 is provided with an internally threaded opening for the reception of the threaded inner end of an influent tube 17 that extends through the base 11 and is provided with a nipple 18 to which may be attached a flexible hose or the like leading from a source of fluid supply.

The base 11 is approximately ovate in general contour and its inner face is rounded or concaved in order to close the vulva while 70 the interior of the base is hollow and forms a chamber into which the fluid to be discharged will flow.

In the outer face of the base 11 is a threaded opening of large diameter, and into this 75 opening is screwed a threaded disk 20 that carries a discharge nipple 21 to which may be connected a discharge pipe, it being observed that the disk 20 may be rotated in order to adjust the nipple circumferentially of the 80 nipple 18, and thus present the discharge nipple in a position most convenient for the operator, this being of considerable importance in practical use where the position of the patient varies.

The base of the nipple 18 is provided with 85 a shoulder 22 that abuts against the outer face of the disk 20 and by screwing the nipple and tube 17 tightly into the threaded opening in the head 18 all danger of leakage 90 around the influent tube is prevented, and at the same time a lock is formed which holds the disk 20 in any position of circumferential adjustment.

It will not, of course, be necessary in all 95 cases to employ screw threads as the connecting means between the disk and the vulva closing base, inasmuch as these parts may be provided with interfitting flanges, and, if necessary, a suitable packing ring may be introduced 100 between them, as shown, for instance, in Fig. 5.

I claim:—

1. In a syringe, a connected head and base, the latter being hollow and provided with an 105 enlarged face plate, said plate having an opening, a disk circumferentially adjustable within said opening and carrying a discharge nipple that communicates with the interior of the base and is adjustable with the disk, 110 an influent tube passing through an opening in the disk and having a threaded connection

with the head member, said tube having a shouldered nipple engageable against the outer face of the disk and forming a lock to hold the latter in adjusted position.

- 5 2. In a syringe of the class described, a connected head member and base, the latter having an enlarged face plate and being hollow to collect the discharge, said face plate having a circular opening, a disk circumferentially adjustable in said opening, a discharge nipple carried by the disk and adjustable therewith, an influent tube extending through a central opening in the disk and having a threaded end engaging with a threaded opening in the head member, said tube being provided with a shouldered nipple that engages against the outer face of the disk and binds the latter in adjusted position, and a detachable cap piece carried by the head member.
- 10 15 3. In a syringe of the class described, a head member and base connected by integral

spaced bars, said head member having an internally threaded opening and the base being hollow and enlarged to close the vulva, said base having a threaded opening in its outer face, a threaded disk mounted in said opening, a discharge nipple carried by the disk and adjustable therewith, an influent tube extending through a central opening in the disk and threaded at its inner end to engage with the threaded opening of the head member, said tube being provided with a shouldered nipple arranged to bind against the outer face of the disk and hold the latter in adjusted position.

In testimony that I claim the foregoing as my own, I have hereto affixed my signature in the presence of two witnesses.

FRANK C. BARNES.
